UNITED STATES PATENT OFFICE

CHARLES D. CUMMINGS, OF TULLY, NEW YORK, ASSIGNOR OF TWENTY-FIVE PER CENT TO LEO E. FULLER, OF SYRACUSE, NEW YORK, AND FORTY-NINE PER CENT TO ALEXANDER F. FULLER AND CHARLES A. ALLEN, BOTH OF PORTSMOUTH, NEW HAMPSHIRE

ATTACHMENT FOR HAMMERS

Application filed April 16, 1928. Serial No. 270,540.

This invention relates to a new and improved attachment for hammers.

In using hammers, particularly of the type called machinist hammers, it is frequently necessary that the weight of the hammer be varied in using it for different purposes. This is usually accomplished by having hammers of this type of different sizes which necessitates the expense of the hammers themselves and the necessity of carrying them from job to job.

It is also desirable in using hammers of this description to have striking faces of different degrees of hardness because hammers of this type are frequently used to drive out bolts by striking them on the threaded end, and if the striking surface of the hammer is of a material softer than the material of which the bolt is made there will be less liability of upsetting the threads in the end of the bolts which would render it unfit for further use.

The main object of my invention is to provide a detachable device which may be used with a machinist hammer to add weight to the head thereof when desired.

Another object is to provide a detachable device of the character just described which will itself become, if desired, a striking surface for the hammer which will be softer than the striking surface or pawl of the hammer itself.

Another object is to provide a means for retaining my device in position on a hammer and additional means for facilitating the removal of the device from the hammer.

Other objects and advantages relate to the size, shape and relation of parts all as will more fully appear from the following description taken in connection with the accompanying drawings in which:

Figure 1 is a side elevation of a machinist hammer with the handle partially broken away and showing, in section, my device in position on the hammer.

Figure 2 is a perspective view of my device. It will be understood that the exact shape of the rear end or peening end of the hammer may be varied and that the interior of my device may be changed to accommodate different sizes of hammers but for the purpose

of describing my device and its operation I have here illustrated a hammer head —1— having a rear end —2— formed with a shoulder —3— adjacent its rear end and having the usual handle —4—. My auxiliary device —5— is cylindrical in shape with the rear end —6— preferably slightly larger in diameter than the front end —7—. The rear end —6— is solid, as shown in Figure 1, and has a flat rear or striking face —8—. I provide in the forward end of my device a centrally located circular aperture —9— of a size to fit over the shank —10— of the rear end of the hammer and abut against the main body —11— of the hammer head.

For the purpose of retaining my device in position I provide in the inner surface of aperture —9— an inwardly extending spring —12— held in position by a screw —13— and adapted to bear against shoulder —3— to releasably hold my device —5— in position on shank —10—. Spring —12— has its inner end —14— bent outwardly so that it will conform to shoulder —3—. A hole —15— leading outwardly from aperture —9— is provided for the reception of end —14— of spring —10— when the same is depressed to permit the removal of my device —5— from shank —10—.

On the surface of portion —7— I provide an angular lug —16— having its front face —17— flush with the front edge —18— of my device. Lug —17— slopes downwardly and rearwardly and merges into portion —6—.

My device is designed not only to add weight to the hammer head when it is in position but also to provide an auxiliary striking surface for the hammer of a material softer, and a material of which the hammer head itself is made. I, therefore, contemplate using brass or lead or other appropriate material in constructing my device depending upon the degree of softness which is preferably for the use to which it is to be put.

The lug —16— above mentioned is provided so that a place will be provided which may be struck by a hammer or other implement for the purpose of assisting in the re-

moval of the device if the same should be too tightly in position for removal by hand.

It will also be understood that the size of my device may be changed as desired as may its particular shape.

5 Although I have shown and described a specific structure and form of my device as an exemplification of an embodiment of my invention I do not desire to restrict myself to the exact shape or form as various changes 10 may be made within the scope of the appended claim.

What I claim is:

In a device of the class described, a main body having a recess in one end adapted to 15 receive the peen of a hammer, a spring positioned in the recess adapted to engage the peen to releasably hold the body in position, and a lug extending laterally from the body, said lug being of a height to extend outwardly beyond the body of the hammer to provide a striking surface.

In witness whereof I have hereunto set my hand this 31 day of March, 1928.

CHARLES D. CUMMINGS.
